(21) Appl. No.: **29/388,025**

(57) **CLAIM**

The ornamental design for a door-handle connector having a handle interface made of glass, as shown and described.

(22) Filed: **Mar. 23, 2011**

DESCRIPTION

(51) **LOC (10) Cl.** **08-06**

FIG. 1 is a perspective view of a door-handle connector having a handle interface made of glass, showing environment that is not part of the door-handle connector;

(52) **U.S. Cl.**

FIG. 2 is a perspective view of the door-handle connector of FIG. 1;

USPC **D8/300; D8/310**

FIG. 3 is a front elevation view of the door-handle connector of FIG. 1;

(58) **Field of Classification Search**

FIG. 4 is a left-side elevation view of the door-handle connector of FIG. 1, with a right-side elevation view being a mirror image thereof, and top and bottom plan views being similar to FIG. 4; and,

CPC **E05B 1/0015**

FIG. 5 is a back elevation view of the door-handle connector of FIG. 1.

USPC **D8/300, 301, 302, 307, 331, 315, 321,**

The broken lines in some figures are for illustrative purposes only and form no part of the claimed design.

D8/343, 349, 400, 310; D7/393, 396;

In addition, the oblique lines shown in the Figures demonstrate transparency or translucency.

49/460; D16/130, 134, 135, 137;

16/110.1, 414, 441, 412; 385/112

See application file for complete search history.
